CHAIN LINK

Paul Patz and Edward A. Graetz, Pound, Wis.

Application June 28, 1948, Serial No. 35,668

6 Claims. (Cl. 74—249)

1

This invention relates to stable cleaning devices.

An object of this invention is to provide a stable cleaning device embodying an endless conveyor which is adapted to move the manure from the rear of the stalls and discharge the same outside of the stable.

Another object of this invention is to provide an improved endless conveyor which includes a chain and a plurality of laterally projecting scraper blades which are fixed to the links and move over the bottom of the trough within which the material is discharged from the stall floor.

A further object of this invention is to provide an improved endless chain conveyor wherein the links of the chain have secured thereto a shield or guard for protecting the links against wear on the concrete trough.

A further object of this invention is to provide an improved conveyor chain formed of detachable links which are so connected together that they can be readily disconnected, but will not become accidentally disconnected. These links are also so constructed that they may rock endwise relative to each other, so that the conveyor may be extended over horizontal and inclined surfaces.

With the above and other objects in view, our invention consists in the arrangement, combination and details of construction disclosed in the drawings and specifications, and then more particularly pointed out in the appended claims.

In the drawings,

Figure 1 is a plan view, partly in horizontal section, of a stable cleaning means constructed according to an embodiment of this invention.

Figure 2 is a sectional view taken on the line 2—2 of Figure 1.

Figure 3 is a fragmentary sectional view taken substantially on the line 3—3 of Figure 2.

Figure 4 is a detail end elevation of one of the conveyor idler wheels.

Figure 5 is a detail side elevation, partly broken away and in section, of the outer end of the conveyor structure.

Figure 6 is a fragmentary sectional view taken on the line 6—6 of Figure 1.

Figure 7 is a fragmentary sectional view taken on the line 7—7 of Figure 1.

Figure 8 is a fragmentary sectional view taken on the line 8—8 of Figure 1.

Figure 9 is a fragmentary longitudinal section of the conveyor chain.

Figure 10 is a detail side elevation of a portion of the chain.

2

Figure 11 is a sectional view taken on the line 11—11 of Figure 9.

Referring to the drawings, the numeral 15 designates generally a stable formed with a plurality of stalls 16, and the stable 15 includes a floor 17 which is formed with a trough 18 extending across the rear ends of the stalls 16 and also extending lengthwise of the stable 15.

The trough 18 has movably disposed therein 10 an endless conveyor chain generally designated as 19 and the chain 19 has fixed thereto a plurality of conveyor blades 20. The chain 19 is formed of a plurality of connected links 21 as shown in Figures 9 and 10, and each link 21 has secured 15 thereto a shield 22 so that the link will be protected against wear when the chain is moving along the trough 18 and may rub against one side of the trough.

Each conveyor blade 20 includes an elongated 20 blade member 23 having a right angular inner end portion 24 which is welded or otherwise fixedly secured as indicated at 25, to a link 21. The blade structure 20 is adapted to scrape along the bottom 26 of the trough 18 so as to move the 25 material which is discharged into the trough from the stalls 16.

The chain 19 engages about idler pulleys or 30 wheels 27 which are rotatably supported at the corners of the trough 18. The chain 19 is extended from the trough 18 and in the present instance an upwardly inclined ramp 28 extends from the trough 18 and extends through the wall 29 of the stable 15, terminating at a point outside of the stable so that the material which is moved from the trough 18 may be carried outwardly and upwardly for discharge into a receiver or collector 30.

The chain 19 is moved or operated by means of 35 a motor 31 disposed at the outer and upper end of the ramp 28. A sprocket wheel 32 is rotatably carried by a bearing means 33 and the wheel 32 is connected to a speed reduction gearing 34 of conventional construction which is connected with a pulley 35 operated from the motor 31 by a belt 40 45 36. At the lower or inner end of the ramp 28 where the conveyor returns to the trough 18 there is positioned a chain guiding shoe 37 which is dependably carried by a support 38.

An idler wheel 39 is rotatably carried by a bearing 40 fixed to the floor of the stable between the opposite runs of the trough 18 where the latter communicates with the inner lower end of the ramp 28. The idler wheel 39 includes a plurality of radially disposed teeth 41 for engagement with 50 55 the links of the chain so as to hold the chain 19

with the blades 20 in contact with the bottom of the trough 18.

At the point where the chain enters the lateral portion of the trough 18 and forms a right angular turn there are provided two idler wheels 42 which are dependably carried on a shaft 43 supported from a horizontally disposed shaft supporting bar 44 which extends across the trough 18. At other corners of the trough 18 the idler wheels 27 are rotatably carried by up-standing studs 45 which extend upwardly from the bottom portion of the trough 18.

Each chain link 21 is formed of an elongated rod which is bent between the ends thereof to form a teardrop loop 46, and the ends of the rod are then secured together in parallelism and bent backward toward the loop 46 as indicated at 47. A transversely extending locking bar 48 is welded to the reverted ends of the rod, and bar 48 is of a length slightly greater than the width of loop 46 at the large end of the latter so that in order to separate one link from another, one of the links must be swung endwise to substantially a right angle relative to the other link and then rocked laterally.

In the use and operation of this device, the material removed from the stalls 16 is discharged into the trough 18 which extends across the rear of the stalls. The material discharged into the trough is removed by operating the motor 31 which will move the conveyor structure, the material being moved along the bottom of the trough and then upwardly along the right side of the ramp 28 and finally discharged in an elevated position into the receiver or collector 30. In the present instance the conveyor moves downwardly along the left side of the ramp 28, but it will be understood that the conveyor may be operated in either direction.

With a stable cleaning means as hereinbefore described, the material may be discharged into a collector such as a wagon body or the like and may then be delivered to the desired point. This cleaning means will provide an improved means whereby a relatively large stable may be cleaned in a relatively short time, it only being necessary to move the material from the ends of the stalls into the trough and then effect operation of the conveyor.

It is, of course, understood that while the ramp has been herein disclosed as inclined upwardly from the floor of the stable, in certain installations the ramp may be inclined downwardly or where there is a pit or space below the stable floor an opening may be formed in the floor for a discharge of the material into a pit or receiver positioned below the opening.

We do not mean to confine ourselves to the exact details of construction herein disclosed, but claim all variations falling within the purview of the appended claims.

What we claim is:

1. A conveyor chain comprising a plurality of connected links, each link being formed of a rod bent upon itself to form a teardrop loop, the ends of said rod being secured together in parallelism and bent inwardly to form a hook extending over the small end of said loop, a transversely disposed locking bar fixed to the reverted ends of said rod, said bar having a length slightly greater than the width of said loop at the large end of the latter, and a shield fixed to said rod about the reverted ends thereof.

2. A conveyor chain comprising a plurality of connected links, each link being formed of a rod

bent upon itself to form a tear drop loop, the ends of said rod being secured together in parallelism and bent inwardly to form a hook extending over the small end of said loop, the ends of the hook being substantially parallel to the plane of said tear drop loop and sufficiently spaced apart to admit the end of an adjacent link, and locking means precluding disengagement of said adjacent link when the chain is in normally aligned position, said locking means including a transverse bar secured at right angles to the outer extremities of said reverted ends of said rod.

3. A conveyor chain comprising a plurality of connected links, each link being formed of a rod bent upon itself to form a tear drop loop, the ends of said rod being secured together in parallelism and bent inwardly to form a hook extending over the small end of said loop, the ends of the hook being substantially parallel to the plane of said tear drop loop and sufficiently spaced apart to admit the end of an adjacent link, and locking means precluding disengagement of said adjacent link when the chain is in normally aligned position, said locking means including a transverse bar secured at right angles to the outer extremities of said reverted ends of said rod, and of a length slightly greater than the greatest internal width of said loop.

4. A conveyor chain comprising a plurality of connected links, each link being formed of a rod bent upon itself to form a tear drop loop, the ends of said rod being secured together in parallelism and bent inwardly to form a hook extending over the small end of said loop, the ends of the hook being substantially parallel to the plane of said tear drop loop and sufficiently spaced apart to admit the end of an adjacent link, and locking means precluding disengagement of said adjacent link when the chain is in normally aligned position, said locking means including a transverse bar secured at right angles to the outer extremities of said reverted ends of said rod, and of a length slightly greater than the greatest internal width of said loop, but less than the greatest external width thereof.

5. A conveyor chain comprising a plurality of connected links, each link being formed of a rod bent upon itself to form a tear drop loop, the ends of said rod being secured together in parallelism and bent inwardly to form a hook extending over the small end of said loop, the ends of the hook being substantially parallel to the plane of said tear drop loop and sufficiently spaced apart to admit the end of an adjacent link, locking means precluding disengagement of said adjacent link when the chain is in normally aligned position, said locking means including a transverse bar secured at right angles to the reverted ends of said rod, and of a length slightly greater than the greatest internal width of said loop, but less than the greatest external width thereof, and a shield fixed to said rod and extending partly about the loop formed by the reverting of the ends of said rod.

6. A conveyor chain comprising a plurality of connected links, each link being formed of a rod bent to form a tear drop loop, the ends of said rod being secured together in parallelism and bent to form a hook extending over the small end of said loop, the ends of the hook being substantially parallel to the plane of said tear drop loop and sufficiently spaced apart from said plane to admit the end of an adjacent link, and a shield

extending partly about the loop formed by the reverting of the ends of said rod.
